UNITED STATES PATENT OFFICE.

WILBUR J. HEMPY, OF KANSAS CITY, MISSOURI, ASSIGNOR TO HEMPY-COOPER MANUFACTURING COMPANY, A CORPORATION OF MISSOURI.

COMBINATION BORING AND FACING MACHINE.

1,426,987.

Specification of Letters Patent. Patented Aug. 22, 1922.

Application filed December 27, 1919. Serial No. 347,791.

To all whom it may concern:

Be it known that I, WILBUR J. HEMPY, a citizen of the United States, residing at Kansas City, in the county of Jackson and 5 State of Missouri, have invented certain new and useful Improvements in Combination Boring and Facing Machines, of which the following is a specification.

My invention relates to bearing boring 10 and trimming machines and is an improvement over my copending application for bearing boring machines filed February 24, 1919, Serial Number 278,686. The important features of the present invention are, 15 first, novel means for automatically throwing the boring mandrel out of gear with the feed nut after the latter has advanced the former to the end of the thread of said feed nut; and second, means for facing the 20 ends of the babbitt linings of the cylinder block bearings.

In order that the invention may be fully understood, reference will now be had to the accompanying drawings, in which:

25 Fig. 1 is a plan view of the machine in position upon an inverted cylinder block.

Fig. 2 is a fragmentary elevation of a portion of the boring mandrel.

30 Fig. 3 is an elevation of a cam secured in one end of the feed nut.

Fig. 4 is an end elevation of said cam.

Fig. 5 is an end elevation of the machine in position upon the cylinder block, the drive shaft of the boring machine being in cross 35 section.

Fig. 6 is an enlarged section on line VI—VI of Fig. 1.

Fig. 7 is a cross section on line VII—VII of Fig. 8.

40 Fig. 8 is a fragmentary view partly in section of the boring mandrel, the feed nut, and the cam.

Fig. 9 is an enlarged broken plan view 45 partly in section of the machine in position upon the cylinder block and equipped with means for facing the linings of the bearings.

Fig. 10 is a disassembled view of the 50 means for adjusting the mandrel longitudinally during the operation of facing the ends of the bearing linings.

Fig. 11 is an end elevation of one of the facing tools.

55 A, designates the engine cylinder block which is usually provided with three alined

bearings B, lined with Babbitt metal E, in which the crank shaft (not shown) is journaled. Said bearings B are formed integral with transverse supports b, extending from side to side of the cylinder block A, which latter is also provided at its ends with the usual cam shaft bearings C, which coat in locating my machine in proper position upon the cylinder block A, as will hereinafter appear.

60 Referring now in detail to the various parts of my machine, 1 designates a skeleton frame which is shaped to fit directly upon the flange D surrounding the base of the inverted cylinder block A. Said frame 70 1 is provided with bolt holes which register with the usual holes in the flanges D to receive bolts 3, whereby the frame 1 is firmly secured upon said flange D.

65 The frame 1 is provided with transverse 75 bearings 5, 7, 9 and 11, in which a boring mandrel 13 is journaled. Said mandrel 13 is equipped with three cutting tools 15, one for each babbitted bearing B. The mandrel 13 is advanced longitudinally to carry the 80 cutting tools 15 from end to end of the bearings B, through the intermediacy of a feed nut 25 and a projecting element 27, which latter is rigidly fixed to the mandrel 13.

85 The feed nut 25 is secured by suitable means such as a set screw 24 upon a cam 26 journaled upon the mandrel 13, and the rear end of the internal thread 30 of said feed nut 25 tapers to a point 31 and terminates near 90 the adjacent end of the cam 26, leaving an intervening space 29 slightly wider than the thickness of the element 27. Thus when 95 said element 27 reaches the tapered point 31 of the internal thread 30, it revolves in the space 29 and ceases to advance the mandrel 13, and hence danger of damaging the machine should the operator inadvertently fail to stop it after the cutting tools 15 have traversed the length of the bearings B is 100 eliminated.

105 The inner end of the cam 26 has a shoulder 32 which is approximately diametrically opposed to the tapered end 31 of the thread 30 to leave a space longer than the element 105 27, so that after the same has been carried by said point 31 into the space 29 and the direction of travel of the nut 25 is reversed, the shoulder 32 on contacting with said element 27 will shift the same bodily to the 110

right against the thread 30, as indicated by dotted lines on Fig. 6. Then as the feed nut 25 continues to rotate the point 31 will engage the left side of the element 27 and start the same backwardly to the right through the thread 30. One end of the element 27 is beveled as indicated at 33, so that in case the shoulder 32 of the cam 26 should fail to fully shift said thread 27 against the element 30 as shown on Fig. 6, the tapered terminal 31 will engage said beveled end 33 and force the element 27 against the thread 30.

The feed nut 25 is provided at one end with an integral pinion 34, which is driven by a master gear 36 mounted upon a drive shaft 38, in bearings 40 mounted on the frame 1.

The mandrel 13 is provided with a gear 42, journaled in the bearing 9 and having a groove-and-feather connection 44 with said mandrel 13 for the purpose of rotating the same and also to permit said mandrel to slide longitudinally in the gear 42, which is driven by a master gear 46, slidably mounted upon the drive shaft 38 beside the master gear 36, so that it may be shifted out of mesh with the gear 42.

The gears 34, 42, 36 and 46 are proportioned to drive the feed nut 25 slightly faster than the mandrel 13, so that the latter will be advanced by the former from end to end of the bearings B, at relatively low speed. By thus slowly advancing the mandrel 13 with the cutting tools 15, the cut made by each tool at each revolution overlaps the preceding cut and thus leaves the bored surfaces of the respective babbitt linings E smooth throughout their lengths.

The drive shaft 38 is provided at one end with a crank 48 whereby it may be manually operated. It also has a pulley 50, so that it may be power driven where power is available.

52 designates a pair of centering-pins slidably mounted in bearings 54 at the free ends of two arms 56, which latter are provided at their opposite ends with bearings 58. One end of each centering-pin 52 is provided with a handle 60, while its opposite end is adapted to fit snugly within the adjacent cam shaft bearing C, to coact with the bolts 3 in properly centering the boring mandrel 13 in proper relation to the bearings B.

55 The bearings 58 at the right straddle the bearing 11 and are swiveled upon the boring mandrel 13, while the bearings 58 at the left straddle the bearing 5 and are swiveled upon a bushing 64 in which the adjacent end of the boring mandrel 13 is journaled. The bushing 64 is secured in the bearing 5 by suitable means such as a set screw 66 and is provided at one end with relatively fine screw threads 68 upon which a coupling member 70 is threaded. The coupling mem-

ber 70 is provided with a peripheral flange 72 having internal threads 73 for engagement with threads 75 on a companion coupling member 74, with which it coacts in loosely grasping the peripheral flange 76 of a sleeve 78. A set screw 77 is employed to lock the coupling members 70 and 74 together. The sleeve 78 has longitudinal slots 80 extending through one end to render it resilient, so that it may be caused to firmly grip the boring mandrel 13 by means of a set screw 82, threaded into a collar 84 removably mounted upon said sleeve 78.

In practice, the frame 1 is placed upon the inverted cylinder block A in such position as to bring the mandrel 13 into axial alinement with the bearings B, which operation is aided by the centering-pins 52 and the cam shaft bearings C. The frame 1 is then firmly secured in place by the bolts 3. The cutting tools 15 are then adjusted to trim out the babbitt linings E to the desired depth, after which the drive shaft 38 is rotated to drive the mandrel 13 and the feed nut 25 through the intermediacy of the gears 46, 42, and 36 and 34, respectively, until said cutting tools 15 travel from the right end to the left end of the bearings B, and the element 27 is carried into the space 29 by the end 31 of the thread 30. If desired, the boring mandrel 13 and the cutting tools 15 may then be quickly carried backwardly to the starting point at the right end of the bearings B by shifting the gear 46 out of mesh with the pinion 42 and reversing the motion of the feed nut 25 by rotating the shaft 38 backwardly. However, if it is desired to face the ends of the babbitt linings E, the cutting tools 15 are removed from the boring mandrel 13 and facing tools 88 are substituted.

Facing of the ends F is accomplished by shifting the boring mandrel 13 to the right until the facing tools 88 engage and trim the left ends F of the babbitt linings E to the desired point. Shifting of the mandrel 13 to the right is accomplished slowly but positively by rotating the coupling members 70 and 74 in proper direction to screw them to the right upon the threaded portion of the bushing 64. As the coupling members 70 and 74 move to the right they carry the sleeve 78 and the mandrel 13 therewith, which latter is rotated as it moves to the right, by a crank 90, which is slipped upon the rectangular terminal 92 at the left end of said boring mandrel 13. After the left ends of the linings E have been faced the tools 88 are removed and the set screw 84 is loosened to allow the sleeve 78 to release the boring mandrel 13, which is then slid to the right to the position shown on Fig. 9, and again secured by tightening the sleeve 78. The facing tools 88 are then replaced in the mandrel 13 and caused to trim the right ends of the linings B, by rotating the

crank 90 and screwing the coupling members 70 and 74 to the left upon the bushing 64.

From the foregoing description it is apparent that I have produced simple and efficient means for boring and facing the linings of cylinder block bearings, and while I have shown and described the preferred form of my invention, I reserve the right 10 to make such changes in the construction, combination and arrangement of parts as properly fall within the spirit and scope of the invention.

Having thus described my invention, what 15 I claim and desire to secure by Letters Patent, is:

1. In a machine of the character described, a mandrel, means for operably holding said mandrel in the alined bearings of a cylinder 20 block, tools carried by said mandrel to operate on the linings of said bearings, means for driving said mandrel, a rotary feed nut loosely embracing the mandrel and having an internal thread tapered at one end and 25 a space at said tapered end, an element fixed to the mandrel and adapted to be advanced by the internal thread until it enters the space at the tapered end of said thread, and a projection in said space to shift said 30 element back into engagement with the internal thread upon reversal of the feed nut.

2. In a machine of the character described, a mandrel, means for operably holding said mandrel in the alined bearings of a cylinder 35 block, tools carried by said mandrel to operate on the linings of said bearings, means for driving said mandrel, a feed nut loosely embracing said mandrel and having an internal thread and a space at 40 one end of said thread, an element fixed to the mandrel and adapted to be advanced by the internal thread until it enters the space at the end of said thread, a cam secured to the feed nut and having a 45 shoulder projecting into the space to shift the element back into engagement with the internal thread upon reversal of the feed nut, means for rotating the mandrel, and means for driving the feed nut in opposite 50 directions at a different speed from that of the mandrel to advance and retract the

same through the intermediary of the element and the internal thread.

3. In a machine of the character described, a rotary mandrel, a frame in which said mandrel is mounted and whereby it is operably held in the alined bearings of a cylinder block, a tool carried by said mandrel to face the ends of the lining in one or more of the bearings, a threaded bushing loosely 55 embracing the mandrel and secured in the frame, a split sleeve adjacent said bushing and secured to the mandrel, and means threaded on the bushing and engaging said sleeve for adjusting the same longitudinally 60 to carry the tool in and out of engagement with the end of the lining.

4. In a machine of the character described, a boring mandrel, a crank for rotating said boring mandrel, a frame in which the 70 mandrel is mounted and whereby it is operably held in the alined bearings of a cylinder block, a tool carried by said mandrel to face the bearings of the lining in one or more of the bearings, a threaded bushing 75 loosely embracing the mandrel and secured to the frame, a split sleeve adjacent said bushing and secured to the mandrel, a marginal flange on one end of said sleeve, and a coupling threaded upon the bushing and 80 engaging the flange of the sleeve to adjust the same longitudinally to carry the tool in and out of engagement with the ends of the lining.

5. In a machine of the character described, 85 a rotary mandrel, a tool carried thereby, a rotary feed nut loosely embracing said mandrel and having an internal thread and a space at one end of said thread, an element fixed to the mandrel and adapted to 90 be advanced by the internal thread until it enters the space at one end of said thread, and means in said space to shift said element back into engagement with the internal thread upon reversal of the feed nut. 95

In testimony whereof, I affix my signature, in the presence of two witnesses.

WILBUR J. HEMPY.
